LOUIS CHOLLET, OF PARIS, FRANCE, ASSIGNOR, BY MESNE ASSIGNMENTS, TO LOVELL-McCONNELL MANUFACTURING COMPANY, A CORPORATION OF DELAWARE.

DIAPHRAGM-HORN.

1,173,559.

Specification of Letters Patent. Patented Feb. 29, 1916.

Application filed July 9, 1912. Serial No. 708,405.

To all whom it may concern:

Be it known that I, LOUIS CHOLLET, a citizen of the Republic of France, and resident of Paris, France, have invented certain new and useful Improvements in Diaphragm-Horns, of which the following is a specification.

This invention relates to certain improvements in diaphragm horns, and more particularly to that type in which there is a high speed rotor having a series of impact members adapted to successively engage with the diaphragm or a wear-piece on the latter. In horns of this character, it has been proposed to provide the rotor with a series of impact members rotatable about an axis normal to the diaphragm and so supported that they may recede from the diaphragm in a direction substantially parallel to the axis of rotation, to facilitate the starting of the rotor and to prevent interference when the diaphragm is vibrating with the maximum amplitude and the diaphragm and rotor are out of synchronism. In such a construction if rotatable balls be employed as the impact members, the wear on the impact members may be distributed but it does not permit any distribution of wear on a fixed wear-piece of the diaphragm and necessitates the use of comparatively strong springs to hold the balls in operative position.

My invention involves an arrangement of parts, whereby the axis of rotation may be arranged parallel to the diaphragm and the rotor may be bodily adjusted lengthwise of its axis to regulate the impact and the impact members may have the desired resilient or "free" movement in respect to said axis and the wear-piece.

One important form which my invention may assume involves a mounting of the impact members so that they may move in a direction parallel to the diaphragm upon striking the wear-piece and a positioning of the impact members by springs also acting parallel with the axis of rotation. The impact members upon starting the rotor or in case of interference, may move parallel to the axis of rotation but around one side of the wear-piece. By mounting the impact members between oppositely-disposed springs, the natural imperfections in the ad-

justment of the device and the slight irregularity in the length and size of the springs may be such that certain of the impact members upon engaging the diaphragm may be deflected around the impact member on one side and some on the other, so as to distribute the wear on the impact member to both sides of the latter rather than to the top. Thus the length of life of the impact member may be lengthened and its effectiveness increased.

By arranging the impact members upon axles spaced apart about the axis of the rotor, free space may be left between the impact members so that the rotor upon starting may acquire a slight headway before the first impact member strikes the wear-piece. This is important where a small electric motor is employed as the source of power. The starting is further facilitated by the fact that as the first impact member engages the wear-piece, it may slip endwise and pass the wear-piece, though the spring which is compressed by such action may be an extremely light one and merely serve to normally hold the impact members in proper position lengthwise of its axle. As the rotor acquires speed, the tendency of the impact members to be deflected around the wear-piece will be reduced and the impact members will deliver blows with full force. At the same time, the impact members are nevertheless free, so that they can be deflected around the wear-piece, to avoid positively stopping the diaphragm when the latter vibrates past the normal toward the rotor at the same time that an impact member is delivering a blow.

I may employ balls or beads as the impact members and may mount them with or without free radial play and on rigid, loose, or flexible axles. By making the holes through the members somewhat larger than their respective axles or by permitting radial movement of the axles of the impact members in respect to the axis of the rotor, or by making the axles of the impact members flexible, I may utilize the action of centrifugal force alone for holding the impact members in operative position. In such constructions, the springs may be omitted and the impact members held between stops if the axle be fixed, or in case of the use of flexible or loose

axles, the impact members may be rigid on the axles and the bending or bodily movement of the axles relied upon. In case of either flexible or stiff axles, the impact members may be rigidly secured to their respective axles, and an endwise sliding of the axles against the action of the springs may constitute the desired resilient mounting. The impact members may be of any desired form but preferably are circular in cross section and of reduced diameter toward one or both ends.

The cross-section longitudinally, that is, in planes containing the axis of the rotor, should preferably afford contacting surfaces inclined laterally, that is, inclined with respect to said axis, so that the dynamic reaction of impact upon the wear-piece may have a component longitudinally of said axis. A simple form of such member is a ball or bead which may be a sphere. The arrangement and form of the co-operating surfaces of diaphragm, wear-piece and rotor is such that the longitudinal component of reaction of impact tends to force said impact member against the spring which is arranged so as to normally tend to maintain said member against such reaction and in operative relation to the diaphragm wear-piece.

By forming the impact members and wear-piece with surfaces rounded or inclined in the direction of the length of the axis of rotation, the rotor and diaphragm may be readily adjusted so as to secure the desired thrust on the diaphragm by moving the rotor axially. This provides a very simple and efficient means and avoids the necessity of an absolutely accurate drilling of the shaft bearings of the rotor. This means of adjusting is equally applicable even though the rotor assume any one of a large number of different forms; for instance, the rotor may include merely a head with radially-disposed pockets in the periphery thereof and each containing a ball or other impact member. The impact members will be thrown out by centrifugal force to the limiting position, and this position may be determined by a collar encircling the head or by flanges or other enlargements on the impact members. The rotor is preferably driven by an electric motor directly on the main shaft and adjacent to one edge of the diaphragm.

In order to support the entire horn and facilitate its attachment to a vehicle or other support, I employ a bracelet which preferably connects directly to the motor case, so as to reduce to a minimum the vibrating or loosening action imparted to the retaining screws during the operation of the horn.

Reference is to be had to the accompanying drawings forming a part of this specification, in which similar characters of refer-

ence indicate corresponding parts in all the figures, and in which—

Figure 1 is a face view of a horn constructed in accordance with my invention; Fig. 2 is a side view thereof, a portion of the casing and the diaphragm being shown in section; Fig. 3 is a side elevation of a slightly different form of rotor from that shown in Fig. 2; Fig. 4 is a top plan view of the rotor shown in Fig. 3, a portion thereof being broken away; Fig. 5 is a side view of one of the axles forming a part of the rotor; and Fig. 6 is a side view of one of the beads or impact members forming part of the rotor.

In my improved construction, I employ a rotor *a* mounted upon a shaft *b* driven by an electric motor in a casing *c*. In the form of rotor illustrated in Fig. 2, I employ two disks *d*, which support between them a plurality of flexible metallic axles *e*. These axles are preferably substantially parallel to the shaft *b* and have their end supported in the disks *d* so as to leave free space between the axles. They are shown in Fig. 2 as comprising flexible wires, the center portions of which may move laterally, due to the flexibility of the wire. Upon each axle or pivot is an impact member *h*, preferably in the form of a ball free to slide longitudinally of its respective axle. Each ball is held intermediate of the ends of the axle by two light springs *g*, each abutting against the impact member and against one of the disks *d*.

The rotor is rigidly secured on the shaft, but it preferably adjustable lengthwise of the shaft. Any suitable means may be employed for securing the rotor to the shaft, but in the form illustrated I provide the shaft with screw threads and lock the rotor between two nuts on the shaft.

The entire rotor is supported within a casing *h*, which is held solid in respect to the motor casing *c* by an intermediate column *i*, through which the shaft *b* extends. The casing *h* is provided on its front side with an annular flange *k* encircling a recess or chamber *l*, and this flange forms a support for a diaphragm *m*, carrying a wear-piece or button *o* at its center and against which the impact members *f* may contact upon the rotation of the rotor. The diaphragm is fixed on its seat by means of a casing member *p*, and upon opposite sides of the diaphragm are preferably two gaskets *n* of felt or other suitable material. The casing member *p* has a large central opening *q* surrounded by a flange *q*, which carries the retaining or horn *r*.

The electric motor may be connected to any suitable source of current and when rotated at high speed will cause a rapid succession of blows by the impact members upon the wear-piece *o*. The impact members are thrown out by centrifugal force, so

as to strike the wear-piece, and the parts may be so designed that with the rotor traveling at very low speed, the impact members will not touch the wear-piece. Thus 5 the rotor may be very easily started and as soon as it acquires speed, the impact members will automatically come into operation. The impact members are free to slide lengthwise of the axles, and in case of interference 10 some of them may pass above and some below, so that the wear on the wear-piece will be distributed. The degree of engagement may be varied by using more or less flexible axles or may be secured by a longitudinal 15 adjustment of the rotor. The springs may be comparatively strong, so that there will be a longitudinal movement only to slightly aid the balls or impact members in getting out of the path of the returning diaphragm 20 when the rotor and diaphragm are out of synchronism.

The entire signal may be supported in various different ways, but preferably I employ a bracket γ having yoke arms engaging 25 with opposite sides of the motor casing e and having a base adapted to be held on any support by suitable screws or other fastening means. This bracket by engaging with the motor casing is not subjected to the same 30 vibration as it would be were it connected directly to the casing h adjacent the edge of the diaphragm, and thus the liability of loosening the fastening screws by the vibration, is materially reduced.

35 Instead of making the axles flexible, as shown in Fig. 2, I may make them in the form of solid rods e' as in the form shown in Figs. 3 to 6, inclusive. Here the rods are mounted in two disks d', d' , and the impact 40 members f' are free to move longitudinally of the rods under the action of springs g', g . The impact members may, if desired, be rigid on the rods and the rods loose in the disks so as to move longitudinally within 45 their bearings. Instead of this, the impact members may have openings therethrough some larger than the rods and may move out, due solely to centrifugal force, and in this case the springs may be omitted and 50 the collars mounted on the rods for holding the impact members against longitudinal movement.

Having thus described my invention, I claim as new and desire to secure by Letters 55 Patent:

1. A horn or signal including a diaphragm having a wear piece, a rotor having its axis substantially parallel to said diaphragm, including a plurality of impact 60 members independently movable axially of said rotor, said members and said wear piece having surfaces inclined in the direction of the length of the axis of said rotor, and yielding means tending to hold said impact 65 members against axial movement.

2. A horn or signal having a diaphragm and a rotor rotatable about an axis substantially parallel to said diaphragm, said rotor including two heads or disks and a series of relatively-movable impact members supported therebetween, together with yielding means tending to hold said impact members against axial movement. 70

3. A rotor for horns or signals, including two substantially parallel disks or heads, 75 spaced apart at a fixed distance from each other, and a series of impact members carried thereby and supported therebetween, and movable toward and from said disks.

4. A rotor for horns or signals, including two substantially parallel disks or heads, 80 and a series of impact members carried thereby and supported therebetween, and movable toward and from said disks, at fixed distances radially from the axis of said 85 motor.

5. A rotor for horns or signals, including two substantially parallel disks or heads, a series of impact members carried thereby and means for resiliently supporting them 90 therebetween at fixed distances radially from the axis of said rotor and tending to hold said impact members in a predetermined intermediate position.

6. A rotor for horns or signals, including 95 a series of substantially parallel axles movable bodily around the axis of rotation of the rotor, each of said axles carrying an impact member, together with yielding means tending to hold said members in a predetermined position. 100

7. A rotor for horns or signals, including a series of substantially parallel axles movable bodily around the axis of rotation of the rotor, each of said axles carrying an impact member movable longitudinally thereof. 105

8. A rotor for horns or signals, including a series of substantially parallel axles movable bodily around the axis of rotation of the rotor, each of said axles carrying an impact member movable in the direction of the length of said axles, together with yielding means tending to hold said members in a predetermined position. 110

9. A rotor for horns or signals, including 115 a series of substantially parallel axles movable bodily around the axis of rotation of the rotor, each of said axles carrying an impact member resiliently supported against endwise movement, together with yielding 120 means tending to hold said members in a predetermined position.

10. A rotor for horns or signals including a plurality of axles movable bodily about the axis of rotation and normally supported 125 substantially parallel thereto, an impact member slidably mounted upon each axle, and springs encircling said axles for positioning said impact members thereon.

11. A rotor for horns or signals including 130

a plurality of axles movable bodily about the axis of rotation and normally supported substantially parallel thereto, an impact member slidably mounted on each axle, and
5 a spring engaging with each impact member and tending to move it in the direction of the length of the axle.

Signed at Paris, France, this twenty-seventh day of June, A. D. 1912.

LOUIS CHOLLET.
